UNITED STATES PATENT OFFICE.

EDWARD B. HESS, OF NEW YORK, AND LEWIS C. MYERS, OF FREEPORT, NEW YORK,
ASSIGNORS TO ROYAL TYPEWRITER COMPANY, INC., OF NEW YORK, A CORPORA-
TION OF NEW YORK.

TYPEWRITING MACHINE.

Application filed June 11, 1925. Serial No. 36,465.

To all whom it may concern:

Be it known that we, EDWARD B. HESS and LEWIS C. MYERS, both citizens of the United States, the former residing at New York, county and State of New York, and the latter at Freeport, county of Nassau, and State of New York, have invented certain new and useful Improvements in Typewriting Machines, of which the following is a specification.

The invention herein disclosed relates to line lock, margin stop and bell ringing mechanism, and is illustrated as applied to a small portable Royal machine, although various features may be used in machines of other types.

One object of the various constructions disclosed is to provide devices which shall be compact in construction and yet efficient in operation, thus adapting them to be employed in small portable machines. The various details which constitute the subject matter of our invention will be described fully in the specification and covered by the appended claims.

In the drawings:

Figure 1 is a rear view of the carriage and a portion of the frame of the machine showing the main features of the invention.

Figure 2 is a side view of the machine with parts in section.

Figure 3 is a perspective view of the margin stop and associated parts.

The drawings show a portion of a frame A, type key lever B, carriage C, platen D carried thereby, paper table E, a card guide roll shaft F supported by arms f mounted on a rod f' pivoted in the side plates of the carriage, a universal bar G, and a type bar H. So far as the invention is concerned, these parts are or may be generally of any desired construction and they are illustrated in the form in which they appear in the Little Royal machine.

Mounted in the side plates 1 of the carriage is a margin stop rod 2 shown as rectangular in cross-section and having slidably mounted thereon margin stop blocks 3 and 4. The retaining device for these blocks 5 comprises a plate having side members 5 which pass downward on each side of the stop rod and are connected at their lower ends by a screw 6 which passes through ears in the margin stop block and serves as a

pivot for the retaining member or latch. At 55 the other end of the block, the latch member has a portion 7 underlying the stop rod and adapted to engage the teeth 8 on the lower edge thereof. A finger piece 9 which is hollow contains a coil spring 10 which bears 60 against the top of the stop lock and normally retains the detent portion 7 in engagement with the rack teeth 8. When it is desired to move the stop from one position to another, the finger piece 9 is depressed slightly, moving the engaging portion 7 out of the rack and allowing the stop to be moved endwise in either direction by appropriate pressure on the finger piece. On top of the latch member is placed a short plate 12 which is held thereto by means of a screw 11 passing through an elongated slot, thus permitting adjustment of the plate. The other end of the plate has downturned ears 13 which engage the body of the latch member. This 70 plate carries an indicating mark 14 which is adapted to register with a scale 15 carried by the upper edge of the paper table E. In this manner the indicating portion of the stop may be adjusted relatively to the 75 stop itself in order to obtain exact registry between the indicating mark 14 and the gradations on the scale 15. It may be noted that the stop block 3 is usually retained on the stop rod by means of the pivot screw 6 80 and at the other end thereof by means of an inturned portion 16 shown in Figure 2. Each stop is provided with a projection 17 85 and at the other end thereof by means of an inturned portion 16 shown in Figure 2. Each stop is provided with a projection 17 on the front thereof, which is adapted to come in contact with an inwardly projecting 90 pin 18 on the side frame pieces of the carriage. This is to prevent the stop from being moved outwardly far enough to come in contact with the arms f' carrying the card guide roll.

The stop 3 at the right hand side of the machine has the double function of ringing the bell and thereafter operating the line lock. The stop block 3 is therefore provided with a freely swinging trip 19 pivoted at 20 to the body of the block. This has an ear 21 which engages the body of the stop block to prevent movement of the trip in one direction relatively thereto. A portion of the stop block 3 is extended downward and rearward as at 22 and is adapted to operate the line locking mechanism as hereinafter set forth. The stop at the left hand side of the

machine has a projecting portion 23 somewhat similar to the portion 22 which is adapted to contact with the center stop and limit the return movement of the carriage to begin a new line of writing.

A lug 24 on the frame A of the machine carries the bell 25 which is located near the base of the machine and at the rear. The bell trip arm 26 is pivoted at 27 to a bracket 28 which is fast at 29 to one of the rails on the shift frame. The upper end of this bell trip arm has an offset 30 extending rearwardly, which is adapted to be engaged by the trip 19 as the carriage moves towards the left. An offset lug 31 on the bracket 28 limits the movement of the bell trip member 20 in the opposite direction. The hole 33 in the bell trip member through which the pivot screw 27 passes is elongated 20 in the direction of the carriage movement. The spring 32 which is attached to the bell trip member and to the bracket 28 tends to pull the bell trip member toward the left in Figure 1. Since the point of attachment of the spring is between the pivot point 27 and the offset abutment 31, this abutment acts as a fulcrum. Normally the bell trip rod or striker occupies the position indicated at X in Figure 1. When it is moved by engagement of the trip 19 with the upper end thereof, it is rocked on the pivot 27 to the position indicated at Y. As the trip 19 slips off the upper end, the striker swings under the influence of gravity and the spring 32 30 and passes slightly beyond the position indicated at X to a position indicated at Z, wherein it is in contact with the bell. At this time there has been a movement of the striker at the pivot point permitted by the elongated slot 33. The contact with the bell is only momentary and the spring immediately returns the striker to the position indicated at X, wherein it is out of contact with the bell. This construction avoids the usual practice of mounting the striker on a length of flexible wire and permits the striker to lie clear of the bell when in inoperative position.

Attached to the frame of the machine at the rear and lower part thereof is a bracket 34 having ears 35 to which are pivoted corresponding ears 36 of a center stop member 37 by means of a screw bolt 38. The means which fastens the bracket 34 to the frame of the machine also fastens in position a bracket member 39 which has a forwardly extending portion 40 at the lower end thereof in which is threaded a stop screw 41 which acts to limit the movement of an arm 42 projecting from the universal bar frame G. A line lock member 43 is pivoted to the center stop at 44 and lies in front of the same. At the left hand side looking from the rear, it has a bent edge 45 which overlies the edge of the center stop. This line lock member extends

downwardly to a much greater distance from a pivot 44 than it does upwardly, thus enabling a relatively slight movement of the upper end of the member to produce a considerable movement of the lower end thereof. When the portion 45 is engaged by the projection 22 on the margin stop and the line lock member is swung, the lower end thereof is moved into position to overlie the portion 46 on the end of the arm 42 projecting from the universal bar and thus stop movement of the universal bar. The line lock member 43 is swung in the other direction by means of a spring 47 attached to the line lock member at one end and at its other end to a pin 48 on the center stop member. The movement of the line lock member 43 under the influence of the spring 47 is limited by a lip 49 which comes in contact with the center stop member.

After the line has been locked, it is frequently desirable to be able to add a few additional characters. Accordingly there is provided a release key 50 which is pivoted on the usual pivot rod 51 for the front links in this type of machine and guided by the comb guide 52. This release key lever is connected by a link 53 with a projection 54 from the lower portion of the center stop member 37. A depression of the key 50 will pull on the link 53 and rock the whole center stop member 37 about its pivot 38, moving the upper portion of the stop member to the rear and the lower portion toward the front of the machine. The line lock member 43 of course moves with the center stop in this movement. Since the lower end of the line lock member moves in an arc of a circle, it is given sufficient movement by depression of the release key to permit the center stop to be actuated, although this end of the line lock member is still in a vertical plane overlying said universal bar. However, the rearward movement of the upper end of the center stop is sufficient to move the stop and line lock member clear of the portion 22 of the margin stop and the line lock member therefore immediately returns to inoperative position. When the release key is now released, the center stop will engage the end of the portion 22 and the carriage is free to move in letter space direction. It may be noted that one reason for having the line lock member 43 overlie the front face of the center stop and provided with a bent over portion overlying the edge of the center stop is to prevent the end of the member 22 on the margin stop engaging between the center stop and the line lock member. The center stop with the line lock member normally is held in operative position by a suitable spring such as is indicated at 55.

It will be noted that our invention provides a small compact construction of parts which may be manufactured at a relatively

low cost but is capable of performing all classes of work that are performed on the standard sized machines.

Various detail changes may be made without in any way departing from the spirit of the invention, which is to be regarded as limited only by the scope of the appended claims.

We claim as our invention:

- 10 1. In a typewriting machine, line lock mechanism comprising a center stop pivoted to the frame of the machine, a line lock member pivoted to the center stop to lie on the front side thereof and in substantially a parallel plane for its entire length, the upper end of said line lock member also having an offset portion overlying the edge of the center stop, a margin stop having a projection to contact with the offset portion and 15 swing the line lock member so that its lower end overlies a portion of the universal bar frame and prevents further printing.
- 20 2. In a typewriting machine, line lock mechanism comprising a center stop pivoted to the frame of the machine, a line lock member pivoted to the center stop to lie on the front side thereof and in substantially a parallel plane for its entire length and extending downwardly below its pivot much 25 farther than it extends above the same, the upper end of said line lock member also having an offset portion overlying the edge of the center stop, a margin stop having a projection to contact with the offset portion 30 and swing the line lock member to locking position, and a key in the keyboard to swing the center stop and line lock member to inoperative position to permit further printing.
- 35 3. In a typewriting machine, a universal bar frame, a center stop, a bracket to which said center stop is pivoted, an adjustable stop member for limiting the movement of the universal bar frame in one direction, and common means for attaching said bracket and stop member to the frame of the machine.

- 40 4. In a typewriting machine, a universal bar frame, a center stop, a bracket to which said center stop is pivoted, a second bracket, a stop screw carried by said second bracket for limiting the movement of the universal bar frame in one direction, and common means for attaching the two brackets to the 45 frame of the machine.

- 50 5. In margin stop and line locking mechanism for typewriting machines, a margin stop comprising a stop block adapted to slide on a stop bar, a latch plate overlying

the top of said stop block and having at 60 one end depending ears pivoted to the block by a pivot member which passes underneath the stop bar and forms means for retaining the block in position, said latch plate having at its other end a portion engaging teeth 65 on the stop bar and intermediate its ends a plate lying on said latch plate and carrying an indicating line.

6. In margin stop and line locking mechanism for typewriting machines, a margin stop comprising a stop block adapted to 70 slide on a stop bar, a latch plate overlying the top of said stop block and pivoted thereto at one end and having means to engage the stop bar to hold the block in adjusted position, and an indicating plate lying flat 75 on the top of the latch member.

7. In margin stop and line locking mechanism for typewriting machines, a margin stop comprising a stop block adapted to 80 slide on a stop bar, a latch plate overlying the top of said stop block and pivoted thereto at one end and having means to engage the stop bar to hold the block in adjusted position, and an indicating plate lying flat 85 on the top of the latch member, said indicating plate being adjustably retained by means of a screw at one end and having ears near the other end engaging the latch plate.

8. In a typewriting machine, bell ringing mechanism comprising a supporting bracket, a bell striker pivoted thereto, a spring normally urging the upper end of the bell striker in one direction, a stop for limiting this movement, the spring engaging the striker between the pivot thereof and the stop and the pivot passing through an elongated hole in the striker whereby the lower end of the striker may move under its momentum into contact with the bell.

9. In a typewriting machine, bell ringing mechanism comprising a bell, a bell striker normally out of contact therewith and pivotally supported by a pivot passing through 105 an elongated slot therein, a spring normally holding the bell striker in a position out of contact with the bell, and a margin stop for rocking the bell striker, the elongated slot permitting the bell-striker when released 110 by the margin stop to pass through its normal position into momentary contact with the bell.

In testimony whereof, we have hereunto subscribed our names.

EDWARD B. HESS.
LEWIS C. MYERS.
